UNITED STATES PATENT OFFICE.

JAMES FRANK BUCKINGHAM, OF COVENTRY, ENGLAND.

CAM-SHAFT MOUNTING FOR INTERNAL-COMBUSTION ENGINES.

1,418,282.

Specification of Letters Patent. Patented June 6, 1922.

Application filed August 31, 1920. Serial No. 407,230.

To all whom it may concern:

Be it known that I, JAMES FRANK BUCKINGHAM, a subject of the King of England, residing at Coventry, in the county of Warwick, England, have invented certain new and useful Improvements in Cam-Shaft Mountings for Internal-Combustion Engines, of which the following is a specification.

10 This invention relates to cam-shaft mountings for internal combustion engines and has for its object to provide means whereby the shaft can be removed and replaced radially as regards the crankshaft without dismantling the crankcase.

According to this invention, a slot is formed in one wall of the case to permit the passage therethrough of the shaft with its timing gear and the ends of the shaft are 20 carried in bearings on caps which project into the case. The shaft is thus shorter than the distance between the end walls of the case and when the caps have been withdrawn endwise the shaft can be lifted out through 25 the slot, which is normally covered by a plate.

In the accompanying drawings,

Figure 1 is a plan view of a crankcase for a V type twin cylinder engine, and

30 Figure 2 is a central vertical section of the same showing the shafts, etc., in place.

Like letters indicate like parts throughout the drawings.

The crankcase shown comprises a cup A 35 with faces A² to which the cylinders are attached over the apertures Z and a hollow stem B, whilst at the opposite end is an aperture C closed by a cover plate D carrying the starting handle H. The stem B 40 contains the outer bearing E² for the crank-shaft E, G, K and the inner bearing E³ is supported by the web A³ of the case.

On the crankshaft is fixed the gear wheel L by means of a peg L², this wheel meshing with 45 the gear M lying in the space between the web A³ and the outer wall A⁴ of the crankcase. The cam-shaft F carries the gear M, and its bearings F² are mounted in flanged caps N at the ends, both of which are 50 supported on the cup portion of the crankcase.

These caps N are attached to the walls in any suitable manner and each projects inwards beyond the wall of the case, forming cylindrical bearing housings.

In the top of the case is a T shaped slot 55 A⁵ provided with a correspondingly shaped cover O. When this and the caps N are removed, the shaft F and gear M can be lifted out of place and re-fitted radially as regards the crankshaft without any difficulty 60 in meshing the timing gears L and M.

The ends of the shaft may drive, as through dog clutches F³, various accessories, such as an ignition device and oil pump (not shown), carried by the walls of the crank- 65 case.

Parts of the connecting rods are shown at J running on roller bearings J² separated by washers J³, of which the outer one is fixed by the bolt K². 70

What I claim as my invention and desire to secure by Letters Patent of the United States is:—

1. In an internal combustion engine, a crank case, a crank shaft mounted in bearings therein, end walls to said crank case, endwise movable bearing housings carried by each end wall and projecting within said crank case, a cam shaft mounted in said bearing housings and shorter than the distance 75 between said end walls, and a slot in the side of said crank case through which said cam shaft can be fitted and removed radially as regards said crank shaft substantially as set forth. 80

2. In an internal combustion engine as claimed in claim 1, the combination with the cam shaft of a ball bearing at each end thereof and flanged caps attached to the crank case wall by their flanges and having housing 90 portions which project into the crank case and carry the ball bearings, substantially as set forth.

In testimony whereof I have signed my name to this specification in the presence of 95 two subscribing witnesses.

JAMES FRANK BUCKINGHAM.

Witnesses:

ALBERT BROWN,
ANNIE L. WADE.
